UNITED STATES PATENT OFFICE.

GEORGE L. CURTIS, OF POCATELLO, IDAHO.

GATE-OPERATING MECHANISM.

Application filed July 16, 1920. Serial No. 396,674.

To all whom it may concern:

Be it known that I, GEORGE L. CURTIS, a citizen of the United States, residing at Pocatello, in the county of Bannock and 5 State of Idaho, have invented a new and useful Gate-Operating Mechanism, of which the following is a specification.

It is the object of this invention to provide novel means whereby a gate may be operated 10 from a remote point, without causing the occupant of a vehicle to alight.

The invention aims to improve the mechanism whereby swinging movement is imparted to the gate, and to provide necessary 15 adjustments whereby gates of different sizes may be accommodated.

It is within the province of the disclosure 20 to improve generally and to enhance the utility of devices of that type to which the invention appertains.

With the above and other objects in view, which will appear as the description proceeds, the invention resides in the combination and arrangement of parts and in the 25 details of construction hereinafter described and claimed, it being understood that, within the scope of what is claimed, changes in the precise embodiment of the invention shown can be made without departing from the 30 spirit of the invention.

In the accompanying drawings:—

Figure 1 shows in perspective, a device constructed in accordance with the invention; Figure 2 is a sectional detail of the 35 swinging member or arm and parts associated therewith; Figure 3 is a section taken approximately on the line 3—3 of Figure 2; and Figure 4 is a section taken through the 40 upper portion of the gate and showing the transverse member which is attached to the gate.

The numeral 1 denotes a suspension post and the numeral 2 denotes a striking post disposed on opposite sides of a roadway. A 45 third post 3 is located on the same side of the roadway as the post 1 and is connected to the post 1 by a brace 4. The posts 1 and 3 and the brace 4 may be denominated, generally, as a support. A stub post 5 is located between the posts 1 and 3.

The numeral 6 denotes a gate of any desired construction. In the present instance, the gate 6 is shown as comprising a frame 7 connected by longitudinal wires 8, although this construction is not insisted upon. An eye bolt 9 is located in the post, 1, and

below the eye bolt 9, an eye bolt 10 is mounted in the post. The post 1 carries an eye bolt 11 and an eye bolt 12. A rod 14 constituting a guide, is inserted through the eye 60 bolts 9 and 10 and has a head 15 engaging the eye bolt 9. A nut 16 is threaded on the lower end of the rod 14 and bears against the eye bolt 10. A collar 17 is carried by the rod 14 above the eye bolt 10 and is held 65 in adjusted positions on the rod 14 by means of a set screw 18. A rod 19 is mounted in the eye bolts 11 and 12 and has a head 20 cooperating with the eye bolt 11. A nut 21 is threaded on the lower end of the rod 19 70 and engages the eye bolt 12. The inner end portion of the frame 7 of the gate 6 is provided with hangers 22 and 23, the hanger 23 receiving the rod 14, and the hanger 22 receiving the rod 19. The collar 17 is located 75 immediately below the hanger 23 and it will be obvious that the collar may be raised and lowered on the rod 14 and be held in adjusted positions by tightening up the set screw 18. The construction permits the gate 80 6 to be raised and lowered, to accommodate accumulations of snow, and for other purposes.

The numeral 31 denotes a U-shaped arm which may be made from a piece of 85 pipe flattened at its bend, as indicated at 32 for reinforcement, the side portions of the arm 31 being flattened at their ends, as shown at 33, so as to fit against the sides of the stub post 5. A pivot element is mounted 90 on the stub post 5 and engages the parts 33 of the arm 31, to form a pivotal mounting for the arm. Each side portion of the arm 31 is supplied with an attaching member 35, to which is secured a flexible element 36 95 rove through a pulley block 37 supported by an eye bolt 38 on the brace 4. The flexible elements 36 are extended laterally to any desired remote points, so that the gate can be operated from a distant place on either 100 side of the gate.

The numeral 44 denotes a clamp made up of a top member 45 and a bottom member 46, the members 45 and 46 of the clamp being shaped at their ends, to receive the side 105 portions of the arm 31, as clearly shown in Figure 3. Intermediate their ends, the members 45 and 46 of the clamp are united by a bolt 48, and thus the clamp is held on the arm 31 for adjustment longitudinally of 110 the arm. The member 45 of the clamp 44 is provided at its ends with outstanding

studs 49 on which nuts 50 are threaded, the nuts retaining chains 51. One chain 51 is attached to the inner end of a lever 41 fulcrumed at 42 on a bracket 43 carried by the 5 post 3 and the other chain is attached to a lever 52 fulcrumed at 53 on a bracket 54 carried by the post 1.

Counterweights 55 are provided, the same being slotted as indicated at 56, so that they 10 can be slipped readily on the side portions of the arm 31 in advance of the clamp 58. The counterweights 55 are provided with set screws 57 enabling the counterweights to be held on the side portions of the arm 31, in 15 adjusted positions.

Clamp members 58 are held on the side portions of the arm 31 by an eye 59, the clamp members being located between the clamp 44 and the counterweights 55. The 20 numeral 60 denotes, generally, a longitudinally extensible link, including a rod 61 pivoted to the eye bolt 59. The rod 61 is slidable for adjustment in a tube 62 and is held therein by means of a set screw 63 25 threaded into the tube. The tube 62 has a flattened end 64 provided with an opening 65. The numeral 66 denotes a pair of clamp members having ears 67 connected by a bolt 68. The clamp members 66 are provided 30 with cooperating hooks 69 having reduced throats 70. The hooks 69 pass through the opening 65 in the flattened portion 64 of the tube 62. It is to be observed, referring 35 to Figure 2, that when the link 60 is in working position, the hooks 69 cannot be detached accidentally from the opening 65 in the tube 62. The hooks 69 may be engaged in the opening 65, however, if the link 60 is swung upwardly from the position 40 of Figure 2 until it stands at right angles to a tube 71, whereon the clamp members 66 are held by the bolt 68. The tube 71, which may be denominated a transverse member, is provided with seats 72 as shown 45 in Figure 4, the seats being adapted to receive the upper end lower portions of the frame 7 of the gate 6. Bolts 73 pass through the member 72 and engage the upper end lower portions of the gate frame 7.

50 In practical operation, the arm 31 may be swung from a remote point by drawing on the flexible element 36. Similarly, when the gate is in a closed position, as shown in Figure 1, the gate may be swung to an 55 open position, by manipulating either of the levers 41 or 52, the levers imparting swinging movement to the arm 31 through the instrumentality of the chains 51. When the arm 31 is swung on the stub post 5, the link 60 swings the gate 6 to an open position, the arm 31 swinging to the right (Figure 1) until it has passed a vertical line coincident with the axis of the stub post 5. During the closing operation, the member 31 is

swung back into the position of Figure 1, 65 either by drawing on the flexible element 36, or manipulating one of the levers 41—52. The clamp 44 may be shifted along the arm 31 so that the flexible elements 51 will hold the levers 41 and 52 properly balanced. The counterweights 55 may be shifted along the arm 31, to regulate the poise of the arm and to vary the center of mass of the arm. It is possible to move the clamp members 58 along the arm 31 and to 70 lengthen or shorten the link 60, the link being lengthened or shortened by sliding the rod 61 in the tube 62, the set screw 63 serving to hold the link at an adjusted length. Owing to the fact that the length of the link 80 may be adjusted to tilt the position of the arm 31 with respect to the vertical may be regulated, a feature which will be understood readily when Figure 1 is noted. The tube or transverse member 71 may be 85 shifted along the gate 6 by loosening the hook bolts 73 thereby accommodating the device to gates of different sizes, it being possible to lengthen or shorten the link 60, as hereinbefore explained. By loosening 90 the bolt 68, the clamp members 66 may be adjusted longitudinally of the member 71.

Having thus described the invention, what is claimed is:—

In a device of the class described, a gate 95 comprising a frame; means for mounting the gate for swinging movement; a bar disposed transversely of the frame; clamps connecting the bar with the upper and lower portions of the frame, whereby the bar may 100 be adjusted longitudinally of the frame; a third clamp mounted for vertical adjustment on the bar; means for holding the third clamp in adjusted positions longitudinally of the bar; a U-shaped arm; means 105 for mounting the arm at its lower end for swinging movement; counter weights longitudinally adjustable on the side portions of the arm; means for holding the counter weights in adjusted positions on the side 110 portions of the arm; a fourth clamp adjustable on both side portions of the arm, longitudinally of the arm; means for holding the fourth clamp in adjusted positions on the arm, longitudinally of the arm; a longitudinally adjustable link pivotally connected at one end with the fourth clamp; means for assembling the link detachably with the third clamp; means for holding the link at adjusted lengths; and means for 115 imparting swinging movement to the arm.

In testimony that I claim the foregoing as my own, I have hereto affixed my signature in the presence of two witnesses.

GEORGE L. CURTIS.
